UNITED STATES PATENT OFFICE.

CLIFTON D. PETTIS, OF NEW YORK, N. Y.

CASTING MOLD.

Application filed April 23, 1923. Serial No. 633,822.

This invention relates to molds for casting metal but more particularly to such as are commonly designated "permanent molds", and has for its primary object to 5 provide a simple and efficient mold of this type which is adapted to chill a portion or portions of the casting. The particular design of mold which I have chosen to illustrate the principles of my invention is intended for the casting of railway brake shoes 10 but it should be clearly understood that these principles are equally applicable to molds for other articles.

Further objects of my invention are to 15 provide a mold of the type described in which chill blocks may be quickly and easily inserted for each casting operation of the mold and removed in the same manner at the completion of such operation, to facilitate 20 the pouring of the molten metal into the mold, to provide an improved form of chill construction, to facilitate the withdrawal of the casting from the mold, and in general 25 to provide a simplified and improved mold construction.

The many other objects and advantages 30 of my invention will be better understood by reference to the following specification when considered in connection with the accompanying drawings, in which:—

Fig. 1 is a side elevation of the mold complete, with the parts in closed position.

Fig. 2 is the same as Fig. 1, plan view.

Fig. 3 is a vertical longitudinal section 35 on the line 3—3 of Fig. 2.

Fig. 4 is a plan view of the mold with the cope removed.

Fig. 5 is the same as Fig. 1, end elevation.

Fig. 6 is a transverse vertical section 40 on the line 6—6 of Fig. 2.

Figs. 7 to 15 inclusive are detail views of the chill blocks.

Fig. 16 is a detail view illustrating one 45 method of attaching the upper chill blocks and a reinforcing back plate to the cope, and

Fig. 17 is a bottom plan view of a reinforcing back plate for railway brake shoes.

Referring to the drawings, the casting 50 mold is mounted upon a suitable base A of cast metal and comprises a plurality of separable sections or members forming a flask or holder, each member carrying a corresponding part of the molding receptacle. To this end, the base A is provided with 55 upstanding lugs 20 substantially centrally located, through which lugs passes a pivot

rod 21, this rod passing also through lugs 22 depending from the bottom of the side members B, B of the mold. A cope C is adapted to rest on the side members B, B 60 when these members are in closed position.

In the present embodiment of my invention, each of the members B and C includes a hollow metal casting forming a flask section, the outer walls thereof being preferably perforated as at 25 to provide ventilation. Chambers as 26 in the members B and C permit free circulation of air about the molding receptacle, to be presently described. 70

The walls of the molding receptacle are formed in sections, each composed of a plurality of blocks. At the portions of the receptacle where it is desired to chill the casting, these blocks are preferably of metal. 75 The remaining blocks are preferably formed of some highly refractory material such as carborundum that may be readily molded into the desired form. The blocks are assembled in the several sections or members composing the flask or holder. Thus the side sections of the molding receptacle are shown as comprising blocks D which in the present embodiment are all of refractory material as no chilling action is required at this portion of the receptacle. Ribs, as 30, on the bottom walls 31 of the side members of the flask fit within corresponding grooves in the blocks and properly position these blocks. These ribs preferably run longitudinally of the member and transversely of the block resting thereon. After the blocks have been placed in position in the members, 80

preferably with sufficient spacing to permit the expansion of the blocks and venting of the gases but insufficient to permit the molten metal to flow into the intervening spaces, they are frictionally locked in such position by key or guard plates as at 32. The 85 key plates are secured to the side members by screws 33 or other suitable means. An

upstanding flange or plate, as at 34, may be provided along the inner edge of the bottom wall 31 of each side member to contact with the corresponding flange on the opposite side member when these members are in closed position (Fig. 6). These flanges are preferably slotted, as at 35, as are the metal walls of the flask proper to permit the expansion of the metal, without danger of breakage or distortion during the casting operation. The pivot rod 21 is preferably lo- 100

95

105

110

115

cated with its axis substantially in the plane of the inner contacting faces of the side members of the mold for the purpose to be presently described.

6 A pair of spaced upstanding lugs 36 is provided on the base plate on each side of the mold and these form the supports for pivot rods 37. On each of these rods is revolubly mounted a sleeve 38 provided with a 10 pair of eccentrically mounted rollers or cams, as 39, formed integral therewith or attached thereto. An operating lever 40 is likewise formed on or connected to the sleeve as indicated. Each of the rollers or cams 39 acts between a pair of outwardly projecting lugs, as 41, on the outer wall of the side members B, B of the mold. When the levers 40 are manually raised, the rollers or cams on their respective sleeves act against the upper lugs 41 and cause the side members to swing inwardly to closed position. Similarly when the levers are depressed, the rollers or cams act upon the lower lugs 41 and cause the side members to swing outwardly. This construction is very advantageous as it provides a smooth and positive opening and closing of the mold. Also the conformation of the rollers or cams causes the side members to be rigidly clamped in closed position when the levers are fully raised. The lugs 22 on the side members of the mold are each preferably provided with a stop shoulder, as at 45, acting against the face of the base A to prevent either member swinging beyond the center in the closing movement.

This cam actuating means for the mold members is disclosed and claimed in my pending application, Serial No. 19,811, filed

40 April 1, 1925.

A chill block holder E is provided at each end of the mold. This holder in the present embodiment is open at the ends and at the top and it is centrally divided, as at 50, one-half of each holder being formed on or attached to the flask section of each side member B. As these holders are alike in form, only one will be described in detail. The holder E is provided at its outer end with 45 ribs or flanges, as at 51, projecting inwardly from each of its side walls. When the side members B are moved to closed position, preparatory to a casting operation, chill blocks F are dropped into these holders. 50 The ribs 51 on the holder fit within corresponding grooves 52 in the chill blocks. The chill block F is shown in detail in Figs. 7 to 9 inclusive, Fig. 7 being a top plan view, Fig. 8 a side elevation, and Fig. 9 an end elevation. Each of these blocks is provided with a cavity 53 forming one end portion of the casting chamber, the side and bottom walls of the cavity being a prolongation of the casting chamber walls in the blocks D 55 of the side members. The front face of the

chill block F is preferably beveled, as at 54 (Fig. 7), to facilitate withdrawal of the members B. The side walls of the holder and the ribs 51 thereon project above the block F (Fig. 3) for the purpose which will 70 be presently described. The members B with blocks F attached form the drag of the mold.

The cope C comprises a chambered flask section 60 provided with handles 61 at its ends. Within this flask section are placed blocks H preferably of refractory material. These blocks rest upon the base wall 62 of the flask (Fig. 6) and are preferably cut away, as at 63, to fit the corners formed by the base wall of the flask and the depending flanges 64. These blocks are held in place by a key or guard plate 65 secured to the flask section by screws 66 or other suitable means. This plate 65 is provided with depending ribs or flanges 67 which press against the upper face of the blocks. The center blocks are provided with a cavity 68 to form the usual center lug on the brake shoe, also cavity 68 to hold the core 68' necessary to provide the opening in the center lug of the brake shoe.

The cope section of the flask is provided at each end with a cavity or chamber 69 to receive the upper chill blocks K, K and M, M. The blocks K are alike in form except that the arrangement is reversed. One of these blocks is shown in detail in Figs. 10 to 12, Fig. 10 being a side elevation, Fig. 11 an end elevation, and Fig. 12 a bottom plan view. The blocks M are also alike except that the arrangement is reversed. One of these blocks is shown in detail in Figs. 13 to 15, Fig. 13 being a side elevation, Fig. 14 an end elevation, and Fig. 15 a bottom plan view. The blocks K, K are placed together and inserted at the end of the cope flask before the cope is placed upon the side members. Each of these blocks is provided with a small groove, as 70, on its inner face and these grooves register when the blocks are placed together preparatory to insertion in the cope. Through the passage provided by the combined grooves 70, passes a loop of wire 71 (Fig. 16) which preferably has the portion 72 above the blocks spread to form a head as 72 which extends transversely of the mold in the manner indicated. A similar wire, as at 73, passes through grooves 74 in the opposing faces of the chill blocks M. When a reinforcing back plate, as at 75, (Fig. 17) is to be incorporated in the casting, the blocks K and M are first inserted in the cope, with the wires in place, the plate is next placed against the under face of the blocks with the extremities of the wires projecting through the usual openings 76, and then the ends of the wires are bent outwardly or transversely against the under face of the plate to form a supporting head 125 130

as 72', as indicated in dot in Fig. 16. The spread loops or upper heads of the wires 71 and 73 are each preferably bent inwardly against the top of the flask and thus form a supporting means for these blocks before the cope is placed upon the side members of the flask. The shoulders 77 and 78 on the blocks K and M respectively act against corresponding shoulders on the cope flask to prevent these blocks being forced upwardly during the casting operation. In the present embodiment, the unit supported by the wires 71 and 73 and to be embedded in the casting, comprises the reinforcing back 75, the core 68' and the center lug 75'.

The blocks K in addition to chilling a portion of the casting and holding the wire which attaches one end of the reinforcing back plate to the cope, form one of the end lugs on the brake shoe casting and provide the pouring gate. The molten metal enters the mold through the passage 85 formed in these blocks, one half being in each block. The end lug of the brake shoe is formed in the cavity 86.

The blocks M are mounted in the cope in the same manner as the blocks K and perform all the functions of these blocks except that of providing a pouring gate. One end lug of the brake shoe is formed in the cavity 87. The blocks K and M are respectively provided with corner grooves 88 and 89 to admit and fit the portions of the ribs 51 on the holders E on the side members B, B projecting above the blocks F when the cope is placed upon these members. The chill blocks K and M have tapering walls 90 and 91 respectively which contact with similar tapering walls of the cope cavities or recesses 69 to hold the chill blocks together and further prevent the chill blocks being forced upwardly during the pouring operation.

The mold is prepared for the casting operation as follows:—The side members B are moved to closed position by raising the levers 40. The chill blocks F are next dropped into the holders E. The cope C with the chill blocks K and M in place and supported by the wires 71 and 73 is now lowered upon the side members B, B. The lower portions of the blocks K and M enter the holders E in these members, the portions of the ribs 51 above the blocks F entering the corresponding grooves 88 and 89 in the blocks K and M respectively. These holders not only firmly hold the chill blocks but rigidly position the cope. The base of each of the blocks K and M rests on the lower chill block F and the refractory block next thereto on the same side of the mold as the chill block (Fig. 3). The cope, in addition to being held in place by the holders E through the medium of the blocks K and M, is further positioned by the depending flanges 64 which

fit the inside edges of the key or guard plates 32 (Fig. 6). Previous to the placing of the cope upon the side members, the usual core for the hole in the center lug is placed in the cavity 68'. The molten metal is now poured into the molding receptacle.

When the casting has sufficiently cooled, the cope is lifted, the chill blocks K and M remaining with the casting. The side members B are next moved to open position by means of the levers 40. The casting with the chill blocks F, K and M can now be lifted from the mold. The chill blocks F are then removed from the holders E. Cold chill blocks are now substituted for the corresponding blocks just removed and the mold is immediately ready to be again closed to receive a new pouring.

By constructing the pouring gate in the chill blocks, the walls of the passage through which the molten metal enters the mold are always cold. This is very advantageous as the metal does not stick to cold walls. It should be noted that in the selected embodiment of my invention the molten metal on entering the casting chamber first strikes against refractory blocks and then flows against the chills. The particular design of mold which I have illustrated is intended to chill the end portions and end lugs of the casting, but it will be obvious that any area on the casting may be chilled in a similar manner. By mounting the blocks F, K and M in the side members and cope, no regular end members of the mold are required.

One of the most important features of my invention is the simplicity with which the chill blocks may be incorporated in and removed from the mold. If the chill blocks are so located in a mold that they cannot be conveniently removed, it is necessary to allow the entire mold to become cold before it may be again used in a casting operation. This necessarily involves loss of time and requires the use of a large number of molds to provide an output equal to that of a single mold of my improved type.

I am aware that many changes may be made in the form and arrangement of parts of my casting mold without departing from the spirit of my invention and I consider myself entitled to make all such as fairly fall within the scope of the following claims.

I claim as my invention:

1. A casting mold comprising separable metal flask sections, each carrying a plurality of blocks of refractory material, and one or more chill blocks carried by certain of said sections and co-acting with said refractory blocks to form a molding receptacle, said chill block being readily detachable from the sections when said sections are in open position and rigidly held thereby when said sections are in closed position.

2. A casting mold comprising a base, rela-

1. Relatively movable side sections mounted on said base, a cope section adapted to rest on said side sections, refractory blocks carried by each of said sections, and chill blocks adapted to be mounted on said sections independently of said refractory blocks and to form with said refractory blocks a molding receptacle when said sections are in closed position. 70
2. In a casting mold, a cope comprising a metal flask section, a multipart molding receptacle section of refractory material mounted in said flask section, and a pouring gate mounted in said flask section and composed of blocks arranged contiguously with a channel formed between said blocks to permit the passage of molten metal through the cope. 75
3. In a casting mold, a cope comprising a frame, a plurality of blocks of refractory material mounted in said frame to form a molding receptacle section, and chill blocks supported by said frame, certain of said chill blocks forming the pouring passage of the mold. 80
4. In a casting mold, a cope comprising a metal flask member, a plurality of blocks of refractory material attached to said frame and forming a molding receptacle section, and chill blocks adapted to be attached to said member independently of the attaching means of said refractory blocks and forming the pouring passage of the mold. 85
5. In a casting mold, a cope comprising a metal flask member, a plurality of blocks of refractory material attached to said frame and forming a molding receptacle section, and chill blocks adapted to be attached to said member independently of the attaching means of said refractory blocks and forming the pouring passage of the mold. 90
6. In a casting mold, a sectional molding receptacle provided with a pouring gate, comprising permanent blocks seated in the wall of one of the sections and having a channel formed between them for the admission of molten metal to the casting chamber, said blocks having means adapted to remain with the casting when said wall is withdrawn therefrom. 100
7. In a casting mold, a sectional molding receptacle provided with a pouring gate comprising a pair of permanent blocks seated in the wall of one of the sections and having a channel formed in the opposing walls of the blocks to admit the molten metal to the casting chamber, said blocks having means adapted to remain with the casting when the receptacle is opened to permit the removal of the casting from said chamber. 105
8. In a casting mold, a sectional molding receptacle provided with a pouring gate comprising metal blocks seated contiguously in the wall of one of the sections of the receptacle and having a channel formed by the conformation of their opposing faces for the admission of molten metal to the casting chamber, said blocks being adapted to remain with the casting when said wall is moved away therefrom by the opening of the molding receptacle. 115
9. In a casting mold, a molding receptacle having its walls formed substantially of a plurality of blocks, certain of said blocks being of metal and the remaining blocks being of refractory material, and a pouring gate formed by a pair of said metal blocks arranged contiguously, one of said refractory blocks being disposed opposite the channel in said pouring gate to receive the impact of the molten metal entering said receptacle. 120
10. In a casting mold, a cope comprising a metal flask member, a set of blocks of refractory material mounted in the central portion of said member to form a portion of a molding receptacle, chill blocks supported in the end portions of said cope, and means carried by said chill blocks for attaching a reinforcing metal plate upon the molding face of said cope. 125
11. In a casting mold, a cope comprising a metal flask member, a set of blocks of refractory material mounted in the central portion of said member to form a portion of a molding receptacle, chill blocks supported in the end portions of said cope, and means carried by said chill blocks for attaching a reinforcing metal plate upon the molding face of said cope, certain of said chill blocks forming a pouring gate for the mold. 130
12. In a casting mold, a cope comprising a metal flask member, a set of blocks of refractory material mounted in the central portion of said member to form a portion of a molding receptacle, a pair of chill blocks fitting in a cavity in each end portion of said member, and a wire passing between the chill blocks of each pair and adapted to have its upper end bent to overlie a portion of said flask member to cause said chill blocks to be supported by said member. 135
13. A casting mold comprising a base, relatively movable side members mounted on said base, a cope member adapted to rest on said side members, molding receptacle sections carried by each of said members, holders mounted on said side members, and chill blocks adapted to be placed in said holders and to form with said sections a molding receptacle when said members are in closed position. 140
14. The combination with a permanent mold for making castings, comprising a drag and a sectional cope having a mold cavity therein, of a member for suspending a unit in the mold cavity having on each end a transversely extending head, the sections of said cope being relatively movable to receive said member. 145
15. A permanent mold for making castings, comprising a drag and a cope having a mold cavity therein and being relatively movable to permit the insertion of a unit into said cavity, the cope being provided with open sided grooves extending therethrough and communicating with the mold cavity, and wires extending through said 150

grooves and having angularly disposed means adapted to engage the unit and the cope to suspend the unit in the mold cavity.

16. A permanent mold for making castings, comprising a drag and a cope having a mold cavity therein, said cope including two members having grooves formed partly in one member and partly in the other member and extending through the cope and communicating with the mold cavity, and means extending through said grooves and engaged with a unit and the top of the cope to suspend the unit in the mold cavity.

17. A permanent mold for making castings, comprising a drag and a cope having a mold cavity therein, said cope including two members, and means extending through said cope between said members and engaged with a unit and the top of the cope to suspend the unit in the mold cavity.

18. A permanent mold for making castings, comprising a drag and a cope having a mold cavity therein, said cope including two sections, and a member extending through said cope between said sections to suspend a unit in the mold cavity, said member having a lower head to engage the unit and an upper head to engage the cope.

19. A permanent mold for making castings, comprising a drag and cope having a mold cavity therein, the cope being adapted to be opened to permit the insertion of a unit therein and also being provided with open sided grooves extending therethrough and communicating with the mold cavity,

and wires extending through said grooves and having elongated heads adapted to be arranged transversely of the unit to engage said unit and the cope for suspending the unit in the mold cavity.

20. The combination with a permanent mold for making castings, comprising a drag and a cope having a mold cavity therein, said cope having at least one open sided groove extending therethrough and communicating with the cavity, and means cooperating with said groove for suspending a unit in the mold cavity.

21. The combination with a permanent mold for making castings, comprising a drag and a cope having a mold cavity therein, said cope having at least one open sided groove extending therethrough and communicating with the cavity, and means cooperating with said groove for suspending a unit in the mold cavity, said means having a transversely extending head on each end thereof.

22. The combination with a permanent mold for making castings, comprising a drag and a cope having a mold cavity therein, of a plurality of separable portions constituting said cope and having open sided grooves formed therein adapted to register when the portions are in place, and means cooperating with said grooves for suspending a unit in position within the mold cavity.

CLIFTON D. PETTIS.
